UNITED STATES PATENT OFFICE

2,279,966

HUMIDIFIER

Reginald W. Bulkley, Kansas City, Mo.

Application March 1, 1941, Serial No. 381,407

3 Claims. (Cl. 236—44)

My invention relates to humidifiers and more particularly to humidifiers adapted to be used in connection with air conditioning systems.

In many parts of the country, the water supply for use in humidifiers contains many inorganic salts. These waters are said to be "hard." When they are employed with the usual devices for flowing water over a gas and liquid contact apparatus, alternate stopping and starting of the water supply results in accumulations which soon clog up the spray openings. This is due largely to evaporation of the film of water left on the spray, after the water supply has been shut off. This film of water is evaporated and layer after layer of salts are deposited, which soon clog up the spray.

One object of my invention is to provide a novel humidifier which may be used with hard waters and in which deposits clogging spray openings will be minimized.

Another object of my invention is to provide a humidifier for air conditioning apparatus, which may be used for long periods of time without the necessity of cleaning the spray openings.

Other and further objects of my invention will appear from the following description.

In the accompanying drawing which forms part of the instant specification and are to be read in conjunction therewith and in which like reference numerals are used to indicate like parts in the various views:

Figure 1 is a diagrammatic sectional view of a humidifier and air conditioner.

Figure 2 is a sectional view, taken on the line 2—2 of Figure 1.

Figure 3 is a diagrammatic view showing the electrical connections employed in my invention.

Referring now to the drawing, a casing 1 which may be insulated by insulation 2, houses a motor 3 which drives a blower fan 4. The blower fan is adapted to impel air from the atmosphere through a filter 5 and draw it over a heat exchanger coil 6, to which either a refrigerant or a heating medium may be supplied. The cooled or heated air then passes over a gas and liquid contact apparatus to humidify it. Water from any suitable supply passes over pipe 7 controlled by valve 8 into a spray pan 9. The spray pan is provided with a plurality of openings 10 and is adapted to distribute water over a wire mesh structure 11 giving the water an extended surface. The air is adapted to pass through the water being sprayed over the wire mesh 11 and be humidified. It then passes to the intake opening 12 of the blower 4 and is discharged

from the blower casing 13 through duct 14 to the spaces to which the conditioned air is being supplied. The sides of spray pan 9 are provided with a plurality of openings 15, permitting water to flow through them, if it reaches their level.

A shaft 16 is mounted transversely within the casing 1 for rotation in the bearings 17 and 18. A tubular sleeve 19 surrounds the shaft 16 and is secured thereto by means of pins 20 and 21. Integral with the tubular sleeve 19 is the sheet metal of a bypass pan 22 which has a slanting bottom 23 terminating in a drain spout 24, adapted to discharge water through drain pipe 25 into the drain pan 26 from which the water flows through eduction pipe 27 to a collecting means, if desired, for recycling through pipe 1 or for disposal in any suitable manner. A spring 28 is secured to one arm 29 of a bell crank lever. The bell crank lever 29 is formed with a hub member 30 which is secured to the shaft 16 by means of a pin 31. The other arm 32 of the bell crank lever is connected to an armature 33 adapted to be actuated by a solenoid 34.

Referring now to Figure 3, the primary 35 of the transformer is connected across main line wires 36 and 37. It supplies potential to the secondary 38 of the transformer. The transformer is connected across the winding of the solenoid 34 through a humidostat 39. Normally, the parts are in a position shown in Figure 1, that is with the solenoid 34 unenergized and the spring 28 holding the bypass pan 22 underneath the spray pan 9. It will be obvious that all of the water being furnished to the spray pan will fall into the bypass pan 22 and flow through its drain spout 24 to the drain pan 26 and thence out of eduction pipe 27 for recycling or other disposal. Due to the fact that water will continue to flow through the openings in the spray pan, insufficient evaporation of the water will take place to allow deposits to form. There is no film of water which is adapted to dry such as forms in the humidifier of the prior art. The constant flow of water insures the absence of deposits and the free flowing of water from the spray pan at all times. As soon as the humidostat 39 indicates a lowering of the humidity, the circuit is completed through the winding of solenoid 34. The energization of this solenoid attracts the armature 33 against the action of spring 28 and rotates the bell crank lever and its hub 30, thus rotating the shaft 16 and the bypass pan 22. The rotation of the bypass pan moves it to the position shown in Figure 3 and permits water from the spray pan to spray over the wire mesh 11,

permitting the air to be humidified. As soon as sufficient humidity has been imparted to the air in the space being conditioned, the humidostat 39 will move to open the circuit through the winding of a solenoid 34, thus deenergizing it. This permits the spring 28 to rotate the bypass pan to the position shown in Figure 1, stopping the flow of water over the wire mesh gas and liquid contact structure 11, ceasing the humidification of the air until it is again required in response to the closing of the circuit through the humidostat 39.

It will be seen that I have accomplished the objects of my invention. I have provided a humidifier for use with an air conditioning apparatus which may be used in terrains where only hard water is available. The humidifier will continue to operate over long periods of time without the necessity of cleaning the spray openings in the water distributing means. If water is costly, it may be recycled a number of times by pumping it from eduction pipe 27 to intake pipe 7. If water is not expensive, it may be passed to a drain opening and disposed of.

It will be understood that certain features and subcombinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, I claim:

1. In a humidifier, means for spreading water

over an extended surface, a spray means having small perforations to break up the water into small drops arranged above the spreading means, means to continuously pass water through said perforations to prevent evaporation and mineral deposits thereon, a humidostatically controlled bypass normally disposed between the spray and spreading means to prevent evaporation from the spreading means when the humidity is satisfied.

- 5 2. In a humidifier having means for spreading water over an extended surface, an arrangement for controlling the delivery of water to the spreading means, comprising a perforated pan adapted to continuously receive water arranged to spray the water on the spreading means, a pivoted interceptor pan normally disposed below the perforated pan to bypass the water discharged therefrom, and means coactive with the interceptor pan and responsive to changes in humidity for pivoting the interceptor pan to a non-intercepting position.

- 10 3. In a humidifier having means for spreading water over an extended surface, an arrangement for controlling delivery of water to the spreading means, comprising a perforated pan adapted to continuously receive water arranged to spray the water on the spreading means, a pivoted interceptor pan normally disposed below the perforated pan to bypass the water discharged therefrom, a solenoid for controlling the movement of said interceptor pan, and means responsive to humidity for controlling said solenoid to move the interceptor pan to bypassing position when a predetermined humidity of the air being humidified is reached.

REGINALD W. BULKLEY.
